ELECTRIC CAN PIERCER WITH FREE STRIPPING PUNCH

Charles B. Anderson, Fort Worth, Tex.

Application May 15, 1959, Serial No. 813,540

6 Claims. (Cl. 30—4)

This invention relates to sheet metal piercing devices and has reference to a mechanism for cutting holes in tops of cans containing liquids.

An object of the invention is to provide greater efficiency in a solenoid actuated can piercer.

A particular object is to provide a flexibly mounted punch in such a manner that the effective cutting area is increased during the piercing stroke and decreased during the retracting stroke, thereby providing free stripping of the punch from the hole pierced.

Another object is to provide a punch for cutting holes in sheet metal and wherein the punch edges are designed to reduce the power heretofore required for such piercing operations.

Another object is to provide a punch for piercing sheet metal and wherein there is a shoulder at the base of the punch for bending the excess metal at the end of the cutting operation.

Another object is to provide an electrically operated can piercer wherein the position of the can closes the actuating switch, and wherein the switch is located so as to avoid contact with any spewing liquids from the can.

Another object is to provide an electrically operated can piercer wherein the can to be pierced is tilted beneath the punch to close the actuating switch and wherein contact of the punch on the top of the can opens the switch.

These and other objects will become apparent from the following description and the accompany drawings wherein:

Figure 1 is a vertical section and side elevation of a can piercing device in accordance with the invention.

Figure 2 is a front elevation and broken sectional view of the lower portion of Figure 1 and taken at a right angle with respect thereto.

Figure 3 is an enlarged broken elevational view of a punch assembly in accordance with the invention and showing the same relative to the top of the can to be pierced.

Figure 4 is a bottom plan view of the punch illustrated in Figure 3.

Figure 5 is a broken perspective view showing the upper rim of a can contacting a switch actuating rod.

Figure 6 is an enlarged broken sectional view showing one of the punches and a portion of the punch assembly as the same appears after piercing a can and at the beginning of the retracting stroke.

Figure 7 is a top plan view of the can after the piercing operation and particularly showing the shape of the resulting holes.

Figure 8 is an elevational and broken sectional view of the solenoid and punch assembly.

Figure 9 is a transverse sectional view taken on line 9—9 of Figure 8.

Figure 10 is a transverse sectional view taken on line 10—10 of Figure 2.

Figure 11 is a view similar to Figure 3, but showing a modified form of the invention.

2

Figure 12 is a view similar to Figures 3 and 11 and showing a further modified form of the invention.

Figure 13 is a view similar to Figures 3, 11 and 12, and showing a still further modified form of the invention.

Figure 14 is a top plan view of a can showing the holes formed by the punch assembly illustrated in Figure 13. The embodiment of the invention illustrated in Figures 1 through 6 has reference to a solenoid operated can piercing device 10 including a circular base 11, a concentric semi-cylindrical frame 12 projecting upwardly therefrom and a cylindrical housing 13 mounted on top of the latter. It is to be noted that the upper end 14 of the frame 12 is circular and hollow, and that the open lower end of the housing 13 is joined to the upper periphery of the circular portion by means of a circular rib 15 and matching groove 16 in the housing. Within the lower end of the housing, and integral with the upper circular portion 14, there is an opening 17 defined by spaced parallel upstanding channels 18 on which there is mounted a commercially available solenoid 19. Generally, the solenoid 19 is comprised of a frame 20, an electric coil 21, an armature or plunger 22, a coil spring 23 therearound and a laterally projecting end plate 24 against which the spring bears for normally maintaining the armature in its raised position.

The punch assembly 25 of the preferred form of the invention is best illustrated in Figures 3, 6 and 8 and is comprised of a rigid transverse support 26 which is secured to a U-shaped bracket or adapter 27 which, in turn, is mounted in a hollow lower extension 28 on the lower end of the plunger 22. As shown in Figure 8, the bracket adapter 27 is secured in place by rivets 29 in opposite sidewalls of the extension 28. The transverse support 26 has outwardly and downwardly extending pointed ends 30 which, as will become apparent, supports a pair of punches 31 during the piercing operation. The punches 31 are secured to the bottom of the transverse support 26 by a relatively large rivet 32 which extends into and is headed in the adapter 27.

The punches 31 are of a single sheet of spring steel or the like and are substantially triangular at their outer ends. As shown in Figure 4 the converging edges are provided with a slight convex curve when viewed from below, and which edges are provided with depending knife edges 33, which arrangement includes a depending point 34, hereinafter referred to as a piercing point. The punches 31 generally coincide with the lower surface of the transverse support 26, but the piercing points 34 extend outwardly beyond the pointed support ends 30, and the included angles between the punches 31 and their connecting portion 35 is less than the included angles between the support ends 30 and the transverse support 26. An optional feature is a depending shoulder 36 in each punch 31 at the base or widest portion thereof for bending excess metal inwardly at the end of the cutting operation.

Referring now to Figure 1, it will be noted that the upper inner surface of the semi-cylindrical frame 12 is inwardly inclined, as at a, whereby a can 37 to be pierced may be tilted by manual pressure so as to cause the rear upper rim of the can to contact and raise a depending rod 38, the lower end of which rod is vertically and slidably mounted in the rear portion of the circular upper end 14 of the frame 12. As particularly shown in Figures 2 and 5, there is an enlargement or boss 39 to accommodate the rod 38 which extends upwardly and operates a switch 40 mounted above the upper surface of the solenoid coil 21. There is an offset b in the rod 38 above the frame end 14 for limiting the downward movement of the rod. The switch 40 shown is a micro-switch having an "off" button 41 on its upper end and

an "on" button 42 on its lower end. A laterally extending leaf spring 43 mounted on the armature plate 24 is positioned to contact the "off" button 41, whereas a lower leaf spring 44 is positioned to contact the "on" button 42. The switch 40 and lower leaf spring 44 are mounted on a bracket 45 secured to the side of the solenoid frame 20, and the extending end of said spring is connected with the upper end of the rod 38.

The modified form of the punch assembly illustrated in Figure 11 includes a straight transverse support 46 on the lower end of the plunger extension 28 and has vertical bolts 47 through the ends thereof for supporting punches 48 which are of substantially the same construction as the previously described punches 31. Nuts 49 secure the punches in place and split spring washers 46a are positioned between the punches and the support 46. It is to be understood that the holes, not shown, through the punches are slightly larger than the diameters of the bolts 47, and which construction and arrangement provides for flexible mounting such as that previously described. It is also pointed out that the described construction and arrangement also limits the upward flexible movement of the punches 48.

The form of the invention illustrated in Figure 12 includes a transverse support 51 and otherwise the punch assembly is substantially the same as described in connection with the preferred form of the invention. However, it is to be noted that the integral connecting portion 52 between the punches 53 is slightly bowed in a direction so that the punches 53 do not normally contact the transverse support 51.

The form of the invention illustrated in Figure 13 is comprised of a straight transverse support 54, and while the punches 55 are similar to those previously described, it is to be noted that the depending or piercing ends 56 are oppositely arranged and that the punches are beneath said support. The punches 55 are normally spaced from the support and are mounted on U-shaped springs 57 and secured to the support by bolts 58. It is to be noted that the pierced holes 59 (Figure 14) are oppositely disposed with reference to the holes 60 (Figure 7) in the other described forms of the invention, that is, having corners adjacent the rim of the can 37.

The operation of all forms of the invention is substantially the same. Contact of the point of the punch deflects the flexibly mounted punch and, since the sides of punch converge toward the point, the effective cutting area of the punch is increased. When retracting the punch the opposite is true; that is, upward movement of the punch tilts the same toward its original normal position and provides free and substantially frictionless stripping. It is also pointed out that by reason of the depending knife edges, and their progressive penetration into the metal during the piercing operation, there is a cutting rather than a shearing action. Just prior to the completion of the cutting action, the depending shoulder contacts the metal between the knives and bends the same inwardly of the can.

The operation of the can piercing device illustrated in Figures 1 and 2 is as follows:

The can 37 to be pierced is placed on the base 11 and pressed inwardly of the semi-cylindrical frame 12. Such action causes a tilting of the can and thereby raising the rear upper periphery thereof where the same contacts the projection *a*. The raised can rim raises the rod 38 which, in turn, contacts the "on" button 42 of the switch 40, thus energizing the solenoid 19. Downward movement of the plunger 22 accomplishes the

piercing of holes 60 in the can 37 in accordance with the foregoing description of operation of the punch assembly. The force of the plunger assembly 25 on the can 37 causes the latter to assume a vertical position and thus release the "on" button 42. The upper leaf spring 43 on the solenoid plate 24 then contacts the "off" button 41 and de-energizes the solenoid 20, after which the spring 23 raises the plunger 22 to its normal position.

10 The invention is not limited to the constructions herein shown and described, but may be made in various ways within the scope of the appended claims.

What is claimed is:

1. A punch assembly for piercing holes in sheet metal, 15 said punch assembly comprising: a plunger, a punch having a downwardly directed piercing point at one side thereof, the bottom area of said punch being generally triangular and diagonally positioned relative to the sheet metal surface to be pierced, a flexible mounting on the side of said punch opposite said piercing point, means reciprocating said plunger perpendicularly relative to the sheet metal to be pierced, and means limiting the flexible movement of said punch.

2. A punch assembly for piercing holes in sheet metal 25 as defined in claim 1 and including depending knife edges along the sides of said punch adjacent said piercing point.

3. A punch assembly for piercing holes in sheet metal as defined in claim 1 and including a depending shoulder on the lower surface of said punch and on the side thereof 30 of opposite said piercing point.

4. An electrically operated device for piercing holes in the ends of cans, said device comprising a vertical frame open along one side thereof for receiving the can to be pierced, a solenoid mounted on the upper end of said frame and having its plunger vertically disposed, a punch assembly mounted on the lower end of said plunger and normally above but adapted to contact the can to be pierced, said punch assembly comprising a punch having a downwardly directed piercing point at one side thereof, 35 the bottom area of said punch being generally triangular and diagonally positioned to the upper surface of the can to be pierced, a flexible mounting on the side of said punch opposite said piercing point and connected with said plunger, and means selectively reciprocating said plunger.

5. An electrically operated device for piercing holes in the ends of cans as defined in claim 4, and wherein there is a projection at the upper center inner surface of said frame, a vertical rod slidably mounted inwardly adjacent 50 said projection and adapted to contact the rim of said can, a switch above said projection, and means operatively connecting said rod with said switch.

6. An electrically operated device for piercing holes in the ends of cans, said device comprising a vertical frame open along one side thereof for receiving a can to be pierced, a solenoid mounted on the upper end of said frame and having its plunger vertically disposed, a punch mounted on the lower end of said plunger and normally above but adapted to contact the can to be pierced, said 55 frame including a projection at the upper center inner surface thereof, a vertical rod slidably mounted inwardly adjacent said projection and adapted to contact the rim of said can, a switch above said projection, means operatively connecting said rod with said switch, and means selectively reciprocating said plunger.
